UNITED STATES PATENT OFFICE.

CHARLES J. NASH, OF CHICAGO, ILLINOIS, ASSIGNOR TO UNIVERSAL DRAFT GEAR
ATTACHMENT CO., OF CHICAGO, ILLINOIS, A CORPORATION OF ILLINOIS.

DRAFT-GEAR YOKE.

1,330,087.

Specification of Letters Patent. Patented Feb. 10, 1920.

Application filed May 15, 1912. Serial No. 697,408.

To all whom it may concern:

Be it known that I, CHARLES J. NASH, a citizen of the United States, and resident of Chicago, county of Cook, and State of Illinois, have invented certain new and useful Improvements in Draft-Gear Yokes, of which the following is a specification, and which are illustrated in the accompanying drawings, forming a part thereof.

10 The invention relates to that type of yoke for draft gears which is made the subject of my pending application for Letters Patent Serial No. 664,461, its object being to substantially strengthen the yoke without materially increasing its weight.

15 The invention is fully hereinafter described, and is illustrated in the accompanying drawings, in which—

Figure 1 is a detail perspective of the 20 yoke, some portions being broken away;

Fig. 2 is a vertical central longitudinal section of the yoke, and a detail of the ear construction, showing the yoke in position for service;

25 Fig. 3 is a transverse sectional view of the yoke, taken on the line 3—3 of Fig. 2.

The yoke to which the invention is particularly applicable is especially adapted for use in so-called twin spring gears, in 30 which the springs are mounted side by side, either in horizontal or vertical alignment.

The yoke is of the ordinary U-shaped type, comprising the longitudinal arms 10, 11, connected at their rear ends by a cross 35 member, 12. The forward ends of the longitudinal members are united by side-plates, 13, 14, between which the coupler-bar, 15, enters, and to which it is attached by means of a key, 16, passing through slots, 17, 18, 40 in the yoke-plates and a suitable slot in the bar.

The presence of two springs, as 19, 20, located side by side, necessitates the use of a wide yoke in order to provide a sufficiently 45 commodious spring pocket.

Under pulling strains, there is a tendency to draw the side members 10, 11 of the yoke toward each other. This tendency is resisted by the side-plates 13, 14, acting as 50 columns. Under excessive stresses, it is found that these plates, because of their very considerable width, tend to buckle outwardly.

To overcome this difficulty, I form, as an 55 integral part of the yoke, bridging plates,

21, 22, across the yoke, each extending inwardly from one of the side-arms 10, 11, and each uniting the plates 13, 14. The length of these bridges, measured from the side members of the yoke, is such that their 60 inner margins are spaced apart a sufficient distance to provide an aperture for the inner end of the coupler-bar 15, permitting its abutting engagement with the forward follower-plate, 23. The bridges 21, 22 may be 65 comparatively thin, and consequently they add but little to the weight of the yoke. They reinforce, however, the side-plates 13, 14, and shorten their unsupported portions. It is well known in mechanics that the 70 strength of a column is inverse as to its length. By reinforcing the plates 13, 14, considered as columns, through a considerable proportion of their length, from either end, and thus substantially decreasing the 75 length of the unsupported or unreinforced portion of the column, a very decided increase in columnar resistance is secured.

The cross member of the yoke is thickened intermediate of its ends by a forward 80 extension. The thickened portion is provided with lateral extensions 24, 25, forming draft lug engaging shoulders, and is cored transversely, as shown at 26, 27 and 28, for lightness and to avoid the drawing 85 of the metal in the casting operation. Webs, as 29, 30 and 31, as many as may be found necessary, cross the recesses at each side of the thickened portion to reinforce the corners of the yoke.

90 I claim as my invention—

1. In a draft gear yoke, in combination, a pair of straight longitudinal members, a pair of side plates joining such members and projecting from the forward ends thereof and forming a coupler-butt receiving socket, and a pair of plates joining the rearward ends of the side plates and each extending inwardly from one of the longitudinal members, such last-named plates being 95 spaced apart to provide clearance to permit the inward movement of the coupler butt.

2. In a draft gear yoke, in combination, a pair of side members, a cross member uniting the rear ends of the side members and being thickened intermediate of its ends by a forward extension, such thickened portion projecting laterally at each side of the cross member, and webs crossing the recesses at each side of the thickened portion

3. In a draft gear yoke, in combination, a pair of longitudinal members, a rear end uniting such members, a coupler-receiving socket at the forward end of the longitudinal members comprising forwardly projecting and inwardly inclined top and bottom walls and apertured side walls, and a plate extending inwardly from the forward end of each longitudinal member, such plates 5 joining the rearward ends of the side walls and having their inner edges spaced apart to provide clearance for a coupler butt.
4. In a draft gear yoke, in combination, a pair of side members, side plates uniting 10 the forward ends of such members and forming a throat for receiving the butt of a
- 15

draw-bar, and bridges projecting inwardly from the side members and connecting the side plates.

5. In a draft gear yoke, in combination, 20 a pair of side members, side plates uniting the forward ends of such members, and bridges projecting inwardly from the side members and connecting the side plates, the inner edges of the bridges being spaced 25 apart to permit the movement therebetween of the butt of a draw-bar.

CHARLES J. NASH.
